UNITED STATES PATENT OFFICE.

JOHN ASBURY SMITH, OF HARRISBURG, PENNSYLVANIA, ASSIGNOR TO ELLIOTT-FISHER COMPANY, OF NEW YORK, N. Y., A CORPORATION OF DELAWARE.

REGISTER FOR ADDING-MACHINES.

1,012,463.

Specification of Letters Patent. Patented Dec. 19, 1911.

Application filed November 27, 1907. Serial No. 404,019.

To all whom it may concern:

Be it known that I, JOHN ASBURY SMITH, a citizen of the United States, residing at Harrisburg, in the county of Dauphin and 5 State of Pennsylvania, have invented a new and useful Register for Adding-Machines, of which the following is a specification.

This invention relates to computing devices, totalizers, or registers in general, but 10 more particularly to a totalizer adapted for use in a combined typewriting and adding machine such for instance as the Elliott-Fisher billing machine of commerce. Said machine is exemplified in Patents Nos. 15 820,879 and 829,971 to Laganke and Smith, and includes in its organization a typewriter of the downwardly acting or flat platen type equipped with an adding mechanism, the latter embracing a totalizer 20 mounted on the machine frame and actuating mechanism including a master wheel, rotated different distances by the respective numeral keys of the typewriter, and presented, by the movement of the typewriter 25 carriage, into coöperative relation with successive denominational members of the totalizer. The arrangement of this class of machines is such, that upon the depression of a key, a digit will be printed in a given 30 denominational position of the column being totalized, and the value of such digit is accumulated in the totalizer or register by the simultaneous operation of the particular denominational member which corresponds 35 to the denominational position of the digit printed.

The object of the present invention is to produce a totalizer adapted for use in a machine of the character stated and arranged 40 for the addition of whole numbers and fractions.

To this end the invention consists in mounting within the totalizer or register casing, a series of denominational members 45 or registering wheels representing different denominations, as for instance units, tens, hundreds and thousands of yards, and an additional member or wheel representing fractional values, as for instance eighths, 50 the several registering wheels being arranged for operation by a series of alined primary wheels of uniform dimensions peripherally toothed to engage the master wheel as the latter advances from one pri-

mary wheel to another with the typewriter carriage.

Another object of the invention is to provide a space between the eighths and units of yards wheels to facilitate the reading of the registered total, and to provide for the uniform spacing of all of the idlers in order that in printing a number and a fraction on the work sheet a space need not be left between the fraction and the number, since such spacing is not customary.

Other objects subordinate to those enumerated will appear hereinafter as the description of the illustrated embodiment of the invention is developed.

In the accompanying drawings—Figure 1 is a front elevation of the register. Fig. 2 is a similar view with a portion of the casing broken away. Fig. 3 is a plan view of the register with the top wall of the casing removed. Fig. 4 is a longitudinal section on the line 4—4 of Fig. 1. Fig. 5 is a vertical transverse section on the line 5—5 of Fig. 4. Fig. 6 is a section on the line 6—6 of Fig. 5 looking in the direction indicated by the arrows. Fig. 7 is a detail view of the eighths wheel, and Fig. 8 is a detail perspective view of an operating wheel and one of the gears whereby motion is transmitted from said operating wheel to the eighths wheel.

Each part, wherever shown, is indicated by the same reference character.

Within the register casing 1 are mounted two shafts 2 and 3 located one above the other and journaled in the side walls of the 9 casing. Normally, however, these shafts are stationary and are only rotated during the operation of resetting the register to zero, as will be described.

Rotatably mounted on the upper shaft 2 are five registering wheels a' , b' , c' , d' , and e' . The wheels b' to e' inclusive are equidistantly spaced to accord with the letter space intervals of the typewriting machine, and in the present embodiment of the invention represent units, tens, hundreds and thousands of yards. Each of these yards wheels is what is known as a ten-increment wheel and has ten peripheral teeth bearing upon their end faces the digits 0 to 9 inclusive, which are successively presented before the sight opening 4 in the casing 1 as the wheel rotates. The wheel a' , which repre-

sents eighths, is spaced to the right of the units of yards wheel b' by an interval corresponding to one letter space of the machine and has a smooth periphery upon which is displayed a series of digits ranging from 0 to 7 inclusive. This eighths wheel a' is what is known as an eight-increment wheel, since it has eight increments or units of movement for each complete rotation, to 5 successively display the eight digits upon its periphery opposite the sight opening 4, as distinguished from the other registering wheels, which, during each complete rotation, display successively ten digits on their peripheries. The eighths wheel a' is fixed to or formed integral with a gear wheel 5 so that the two wheels rotate in unison on the shaft 2.

On the lower shaft 3 are mounted five primary or operating wheels a , b , c , d and e , each of which is geared to one of the registering wheels a' , b' , etc. The operating wheels a , b , etc., are of identical dimensions, and being mounted on the same shaft 3, are 10 in alinement. These wheels, like the yard wheels, are provided with peripheral teeth which, in the normal positions of the wheels, are alined so that the master wheel A, which is peripherally toothed to engage the operating 15 wheels, may freely pass from one wheel to another as the typewriter carriage advances from one printing point to the next. The operating wheels b to e inclusive are directly geared to the yard wheels b' to e' inclusive, and upon the operation of any of 20 said operating wheels, movement in like degree is transmitted to the corresponding yard wheels. This is not true of the operating wheel a and the eighths wheel a' operated by it. On the contrary, the fact that the unit of movement of the master wheel is always the same and that it corresponds to the unit of movement of each of the yards wheels renders it necessary to interpose a 25 train of gearing between the wheels a and a' , as each increment of movement of the wheel a when operated by a corresponding increment of movement of the master wheel, must transmit an increment of movement of 30 greater extent to the eighths wheel a' . In other words, when the operating wheel a is given one-tenth of a complete rotation, it must impart one-eighth of a complete rotation to the wheel a' . It is for this reason 35 that the wheel a' is provided with a gear 5, as already stated, and the wheel a is similarly provided with a gear 6 upon the somewhat elongated hub 7 of which the wheel a is mounted; see Fig. 5. The two gears 5 and 40 6 are disposed immediately adjacent to the right hand wall of the casing 1 and are geared together by two idle gears 7^a and 8 meshing with each other and also with the gears 5 and 6 respectively. The gears 5 and 45 6 are of different dimensions, the ratio

being eight to ten. In the present construction, see Fig. 6, the gear 5 has twelve teeth and the gear 6 has fifteen teeth, the intermediate motion transmitting idle gears 7^a and 8 having a similar number of teeth, the 50 purpose of employing a plurality of gears being merely to cause the number wheel to rotate in a direction opposite to the direction of rotation of its operating wheel.

The carrying mechanism, whereby values 75 are automatically transferred from each number wheel to the wheel of next higher denomination when the limit of value of the first named wheel is reached, is not novel, except as it may enter into novel combination with other elements or mechanisms.

Mounted on a transverse shaft 9 is a series of carrying levers 10 each having a long forwardly extending arm 11 and a short depending arm 12. To the arm 12 is secured 80 one end of a spring 13 having its opposite end secured to the rear wall of the casing 1, as shown in Fig. 4. The several springs 13 constitute carrying or transfer motors, since they operate the carrying levers 10. 85 The long arm 11 of each lever 10 has its front end bifurcated to form a locking arm 14 and a guide plate 15, the latter being guided in a kerfed bar 16 extending transversely of the casing.

Pivoted to each locking arm 14 is a transfer dog 17 the lower end of which is designed to engage over a tooth of one of the operating wheels a , b , etc., so that when the transfer lever 10 carrying the dog is operated by a spring 13, the dog will advance the operating wheel one increment and thus cause the corresponding number wheel to be likewise advanced an increment for the purpose of transferring a value thereto. 100 Each of the transfer levers 10 is normally held in an elevated position by a selector 18 or 18^a. The selectors 18 are those which control the transfer levers arranged to operate the wheels b to e inclusive. These 105 selectors are mounted to swing from a transverse shaft 19 and each is yieldingly held in its forward or effective position by a spring 20. Each selector has a downwardly extended arm 21 having its lower end 22 bent laterally to cause it to engage under the lower edge of a transfer lever 10 immediately in rear of a shoulder 23, see Fig. 4. When, however, the lower end of the selector is thrown back to the position indicated in 110 Fig. 4, its retaining end 22 will come opposite a slot 24 extended upwardly from the lower edge of the lever 10, and as said slot is of sufficient dimensions to receive the retaining portion of the selector, the lever will 115 drop down, as seen in Fig. 4, to first advance the adjacent operating wheel and then lock the same by the engagement of the locking arm 14 between two teeth of the wheel, as 120 shown.

In addition to the downwardly extending arm 21, each selector 18 has a forwardly extending arm 25 provided at its extremity with a contact plate 26 which extends between two adjacent operating wheels, to-wit, the wheel served or advanced by the transfer lever controlled by the selector, and the wheel of next lower order. This location of the contact plate on the selector 18 brings it in position to be engaged by a transfer lug 27 projecting from the left hand face of the operating wheel at the right of the selector. Thus when any one of the wheels *b* to *d* inclusive has been operated nine increments to cause the registration of 9 on the number wheel of that particular order, the next increment of movement of said wheel, as for instance the wheel *b*, will accumulate the tenth increment of movement on the wheel *b'*, and, this being the limit of value of said wheel, will cause the transfer lug 27 on wheel *b* to engage the contact plate 26 on the adjacent selector 18, thus urging the selector back to the position shown in Fig. 4 and allowing the transfer lever 10 to drop for the purpose of advancing the wheel of next higher order, to-wit, the wheel *c*, one increment. This transfer movement of the wheel *c* by its transfer lever, will cause the number wheel *c'* to be advanced one increment, thus accumulating thereon the value transferred thereto from the wheel *b'* of next lower order.

For a more complete disclosure of this carrying mechanism just described, reference may be made to the co-pending application of Chas. F. Laganke and John A. Smith, Serial No. 308,209.

The selector 18^a which controls the transfer of values from the eighths wheel *a'* to the units wheel *b'*, is somewhat different from the selectors 18 just described. It is identical with said selectors in so far as its retention of a transfer lever 10 for the wheel *b* is concerned, but unlike the other selectors, it is not arranged to be operated by one of the primary or operating wheels. On the contrary, the selector 18^a is provided with a laterally deflected arm 18^b. The front extremity of this arm is provided with a cam 18^c located adjacent to the left hand side face of the eighths wheel *a'* and in position to be engaged by a transfer lug 18^d carried by said wheel, see Fig. 6. The selector 18^a, therefore, is operated directly by one of the number wheels, to-wit, the wheel *a'*, and serves to control a transfer lever which, when operated, engages and carries one of the operating wheels, to-wit, the wheel *b*. This difference between the selector 18^a and the others of the series is necessitated by reason of the lack of uniformity in the movements of the wheels *a* and *a'*. It is necessary that the wheel *a'* effect the carry-

ing operation once for each complete rotation thereof, but as a complete rotation of this wheel does not represent a complete rotation of its operating wheel *a*, the operating wheel cannot be utilized for the operation of the selector, as is possible with the other operating wheels *b* to *d* inclusive by reason of the fact that said last named operating wheels and the number wheels geared thereto have uniform movements.

The resetting of the number wheels to zero is accomplished by mechanism which includes a series of resetting cams 28 fixed to the shaft 3 to the left of each of the operating wheels *b* to *e* inclusive, and each having a shoulder 29, the several shoulders being normally aligned. On the left hand face of each of the wheels mentioned is a resetting dog 30 urged toward the periphery of the cam by a spring 31. As the shaft 3 and the cams 28 are normally stationary, the rotation of the wheels *b* to *e* will cause the dogs 30 carried thereby to traverse the peripheries of the cams and obviously, when a given computation has been completed, these dogs will be variously located with reference to the shoulders 29, according to the number which happens to be registered at the sight opening. If, however, the shaft 3 is given a complete rotation, the cams 28 will be carried with it and the dogs 30 will be picked up by the shoulders 29 and carried around to restore the wheels to zero. This rotation of the shaft 3 to effect the resetting of the yards wheels geared to the operating wheels *b* to *e* inclusive, is accomplished by means of a resetting lever 31 fulcrumed at the left hand side of the casing, as indicated at 32, and having at its front end a toothed segment or rack 33 which meshes with a resetting pinion 34 fixed to the left hand end of the shaft 3. When the rear end of the lever 31 is swung up the rack 33 will rotate the pinion 34, thus causing the latter to rotate the shaft 3 to reset the wheels in the manner stated. When the lever is thrown back to its normal position, the shaft 3 and the cams thereon, will be reversely rotated, but the wheels will remain stationary, the retention of the wheels being effected by the locking ends 14 of the resetting levers, which will have been depressed during the resetting operation, and by spring urged locators 35 which engage each of the operating wheels *a* to *e*.

It will be noted that thus far no mention has been made of the resetting of the eighths wheel *a'*. This wheel cannot be reset through the medium of its operating wheel *a* as are the several other number wheels, for the same reason that necessitates a variation in the carrying mechanism, to-wit, that a rotation of one wheel does not represent a complete rotation of the other. In order to reset the wheel *a'* independently of

70

75

80

85

90

95

100

105

110

115

120

125

130

its operating wheel, said wheel a' is provided on its left hand face with a resetting dog 30^a arranged to be engaged by a shouldered resetting cam 28^a fixed to the shaft 2. The shaft 2, like the shaft 3, is normally stationary, but when the shaft 3 is rotated to reset the wheels b to e inclusive, a gear 36, keyed to the shaft 3 adjacent to the left hand end thereof, serves to drive a gear 37 keyed to the shaft 2, so that both shafts will rotate. This rotation of the shaft 2 will cause the cam 28^a thereon to coact with the resetting dog 30^a and thus reset the eightths wheel a' to zero simultaneously with the resetting of the other wheels.

As is well understood in the art, it is necessary after each number has been added to the amount previously accumulated in the register, to retract the transfer levers and selectors which may have been operated. This is accomplished by a rocker 38 located below the transfer levers and geared to a slide 39 operated by the typewriter carriage to swing the rocker and thus elevate the levers 10. It is also necessary to retract the levers 10 and selectors 18 and 18^a before the resetting operation and after such operation, because when it is desired to reset, some of the levers may be down, and of course all of them move down during the resetting operation because all of the wheels necessarily move from 9 to 0, thus causing the transfer lugs to throw the selectors back. This resetting of the levers 10 and selectors 18 and 18^a before and after the resetting operation, is effected by the manipulation of the resetting lever 31 which is provided with a cam 40 arranged to operate a slide operating lever 41 connected at its lower extremity to the slide 39. When the resetting lever is operated, the cam 40 will cause the lever 41 to retract the slide 39 to swing the rocker 38 and thus cause the levers 10 to be moved away from the wheels a , b , etc., before the dogs on said wheels have been engaged by the resetting cams. The wheels will then be reset by the continued movement of the lever 31 in a manner already described, and incidental to the resetting, the selectors 18 and 18^a will move back and the levers will drop down. Upon the retraction of the resetting lever 31, however, the cam 40 will again operate the rocker 38, through the medium of the lever 41 and the slide 39, to again reset the transfer levers and selectors to normal position. Thus when the lever 31 has been operated and restored to position, the number wheels, transfer levers, and selectors, will all be reset to position for the performance of another computation. The engagement of the transfer dogs 17 with the operating wheels a , b , etc., is insured by a vibrator 42, operated in a manner well understood in the art by the typewriter car-

riage to urge the dogs 17 forward and thus insure their engagement with the teeth of the operating wheels at the proper time.

Attention is now directed to several distinguishing characteristics of the described register. It will be noted that all of the wheels are of the same diameter and that each series of wheels, to-wit, the number wheels and their operating wheels are alined. Yet, notwithstanding this uniformity of dimensions and alinement, one of the registering wheels, to-wit, the wheel a' has a unit of movement of greater extent than the unit of movement of any other wheel. Furthermore, while the operating wheels are equidistantly spaced, since equidistant spacing of numbers and fractions is usual in the printing thereof, the fractional number wheel, to-wit, the eightths wheel a' , is spaced from the yards wheels by a considerable interval to facilitate the reading of the number registered at the sight opening. Attention is also directed to the fact that the parts are arranged in the casing in a manner which is distinctly economical of space, the train of gearing between the wheels a and a' being located at one extreme side of the casing and the train of gearing between the two shafts being located at the other side of the casing and spaced therefrom by only such interval as is necessary for the accommodation of the resetting lever and gear.

It is thought that from the foregoing, the construction and operation of this register, designed for addition in yards and eightths, will be fully understood, but I expressly reserve the right to effect such changes, modifications and variations of the illustrated structure as may come fairly within the scope of the protection prayed.

What I claim is:

1. In a register of the character described, the combination with an alined series of registering wheels non-uniformly spaced apart, of a uniformly spaced series of operating wheels arranged to operate the registering wheels and having their teeth normally alined.

2. In a register of the character described, the combination with a series of ten-increment wheels, of an eight-increment registering wheel, all of said registering wheels rotating upon the same axis and the eight-increment wheel being spaced from the adjacent ten-increment wheel a greater distance than the ten-increment wheels are spaced from each other, and a series of alined, equidistantly spaced ten-increment wheels each arranged to operate one of the registering wheels, the teeth of said operating wheels being normally alined to facilitate their successive engagement by a toothed master wheel.

3. In a register of the character described,

- the combination with a casing and a pair of parallel shafts, of a series of registering wheels mounted on one shaft, a series of operating wheels mounted on the other shaft, 5 certain of said operating wheels being directly geared to certain of the registering wheels, a train of gearing between one of the operating wheels and its registering wheel, said train of gearing being mounted 10 immediately adjacent to one side of the casing, gearing connecting the two shafts and located adjacent to the opposite side of the casing, means whereby the rotation of the shafts will effect the resetting of the wheels, 15 and means for rotating one of the shafts.
4. In a register of the character described, the combination with a pair of parallel shafts, of a series of registering wheels mounted on one shaft, a series of operating wheels there- 20 for mounted on the other shaft, means for rotating the shafts simultaneously in opposite directions, and means whereby such opposite movements of the shafts will effect the resetting of the registering wheels.
5. In a register of the character described, the combination with a pair of parallel shafts, of a series of registering wheels mounted on one shaft, a series of operating wheels mounted on the other shaft and geared to 25 the registering wheels, resetting cams mounted on one shaft, resetting dogs mounted on certain of the operating wheels and coacting with the resetting cams, a resetting cam mounted on the other shaft, 30 a resetting dog mounted on one of the registering wheels and coacting with the last named resetting cam, and means for rotating the shafts in opposite directions to effect the resetting of the registering wheels 35 through the coaction of the resetting cams and dogs.
6. In a register of the character described, the combination with a casing and a pair of parallel shafts, of a series of registering 40 wheels mounted on one shaft, a series of operating wheels mounted on the other shaft, certain of said operating wheels being directly geared to certain of the registering wheels, a train of gearing between one of the 45 operating wheels and its registering wheel, gearing connecting the two shafts, means whereby the rotation of the shafts will effect the resetting of the wheels, and means for rotating one of the shafts.
7. In a register of the character described, the combination with a pair of shafts, of a 50
- series of registering wheels mounted on one shaft, a series of operating wheels therefor mounted on the other shaft, means for rotating the shafts, and means whereby such 60 movements of the shafts will effect the resetting of the registering wheels.
8. The combination with a register, of two normally stationary shafts, a series of operating wheels on one shaft, a series of registering wheels on the other shaft and actuated by the operating wheels, the operating wheels having uniform units of movement and the registering wheels having non-uniform units of movement, and resetting 70 means arranged to simultaneously reset the registering wheels to zero.
9. The combination with a register, of two normally stationary shafts, a series of operating wheels on one shaft, a series of registering wheels on the other shaft and actuated by the operating wheels, the operating wheels having uniform units of movement and the registering wheels having non-uniform units of movement, and resetting 75 means arranged to simultaneously reset the registering wheels to zero, said resetting means including means for rotating the two normally stationary shafts, and connections whereby said shafts will rotate and reset 80 different registering wheels.
10. In a register of the character de- 85 scribed, the combination with a plurality of shafts, of a series of registering wheels mounted on one shaft, operating wheels mounted on another shaft, said operating wheels being geared to the registering wheels, gearing connecting the two shafts, means whereby the rotation of the shafts will effect the resetting of the wheels, and 90 means for rotating one of the shafts.
11. The combination with a register hav- 95 ing an alined series of registering wheels non-uniformly spaced apart and a uniformly spaced series of operating wheels arranged to operate the registering wheels and having their teeth normally alined, of a master wheel arranged to engage and operate the uniformly spaced operating wheels in suc- 100 cession.
- In testimony, that I claim the foregoing as my own, I have hereto affixed my signature in the presence of two witnesses.
- JOHN ASBURY SMITH.
